(57) **CLAIM**

The ornamental design for an ammunition container, as shown and described.

DESCRIPTION

FIG. 1 is a front isometric view of an ammunition container shown in a first configuration;

FIG. 2 is an isometric view thereof, shown in a second configuration;

FIG. 3 is a front elevation view of the ammunition container of FIG. 1;

FIG. 4 is a rear elevation view of the ammunition container of FIG. 1;

FIG. 5 is a side elevation view of the ammunition container of FIG. 1;

FIG. 6 is a top plan view of the ammunition container of FIG. 2;

FIG. 7 is a bottom plan view of the ammunition container;

FIG. 8 is a front isometric view of the ammunition container shown in a third configuration;

FIG. 9 is a high angle side view thereof; and,

FIG. 10 is a rear isometric view thereof.

The dash-dash broken lines depict portions of the ammunition container that do not form part of the claimed design. The dot-dot broken lines depict the boundaries of the claimed design and form no part thereof.
